UNITED STATES PATENT OFFICE.

JOHN H. BEST, OF CAMP CODY, NEW MEXICO.

WIRE-STRETCHER.

1,345,310.

Specification of Letters Patent. Patented June 29, 1920.

Application filed January 14, 1919. Serial No. 271,024.

To all whom it may concern:

Be it known that I, JOHN H. BEST, a citizen of the United States, residing at Camp Cody, in the county of Luna and State of New Mexico, have invented new and useful Improvements in Wire-Stretchers, of which the following is a specification.

This invention relates to new and useful improvements in wire stretchers and the 10 principal object of the invention is to provide means for utilizing a pair of ordinary claw hammers as a gripping means for the device.

Another object of the invention is to provide means for rocking said device back and 15 forth to gradually take up the slack in the wire.

Another object of the invention is to provide a device of this character which is 20 simple and durable in construction, reliable and efficient in operation and one which can be manufactured and placed upon the market at a minimum cost.

The invention also consists in certain 25 other features of construction and in the combination and arrangement of the several parts, to be hereinafter fully described, illustrated in the accompanying drawings and specifically pointed out in the appended 30 claim.

In describing my invention in detail, reference will be had to the accompanying drawings wherein like characters denote like or corresponding parts throughout the 35 several views, and in which:—

Figure 1 is a view of the device in use.

Fig. 2 is a section on line 2—2 of Fig. 1.

Figs. 3 and 4 are sectional detail views.

In these views, 1 indicates a cross piece 40 having a hole 2 in one end thereof, or, if desired, a cross piece may be formed of tubing. Adjacent each end of the cross piece is an ear 3 having a hole therein and midway the ends of said piece, on the opposite side on 45 which the ears 3 are located is another ear 4, which is also provided with a hole. 5 indicates a clevis pivotally secured to the ear 4 by the pin 6. Chain 7 has one end secured to the clevis and its other end is adapted to 50 engage with the hook 8 on said clevis. The said end of the chain is provided with a hook 9, which may be secured to the wire when the device is to be used for splicing. 10 indicates a pair of ordinary claw ham-

mers, the handles of which are provided 55 with slots 11 at the ends, which are adapted to engage with the ears 3. These ends are pivotally secured to the ears by pins 12. A handle 13 is provided, having one of its ends adapted to engage with the hole 2 in the 60 cross piece 1 for rocking the cross piece on the clevis.

The hammers are arranged with the claws 65 adjacent each other and the cross piece is rocked to place one hammer in advance of the other. The wire is then placed in the claw of this hammer and by rocking the cross piece this hammer is retracted so as to pull the wire toward the post while the other hammer is advanced. This advanced 70 hammer is then connected with the wire and the cross piece rocked in the opposite direction. This action will free the first hammer from the wire and the wire will be again pulled toward the post. As illustrated in 75 Fig. 2, the claws of the several pivoted arms are provided with longitudinal slots extending out through their ends so as to receive the wire being stretched. This action is kept up until the wire is sufficiently tight. 80 The device is held to the post by passing the chain 7 around the same and having one of its links engaging the hole of the clevis. When the device is to be used for splicing 85 wires the hook 9 is secured to one of the wires and the device used as before to bring the ends of the wires together.

I prefer to form the handles of the hammers with a slot 14, so that the hammer engaging part thereof is flexible, so that the 90 handle may be passed into the eye of the hammer head by pressing the two parts of the handle together. After the handle is in place a set screw 15 is forced into the end of the handle to wedge the head thereon. 95

It is thought from the foregoing description that the advantages and novel features of my invention will be readily apparent.

I desire it to be understood that I may make changes in the construction and in the 100 combination and arrangement of the several parts, provided that such changes fall within the scope of the appended claim.

What I claim is:—

A wire stretcher comprising a cross head 105 having a socket extending out through one end thereof, a handle extending into said socket, a pair of spaced laterally projecting

apertured ears carried by the end portions of said cross head, a pair of arms pivoted to said apertured ears, claws carried by the forward ends of said arms and provided with slots 5 extending out through their ends for receiving a wire, a laterally projecting apertured ear carried by the intermediate por-

tion of said cross head and arranged on the opposite side of the same from said pair of spaced laterally projecting apertured ears, 10 and an anchoring device connected to said last named apertured ear.

In testimony whereof I affix my signature.
JOHN H. BEST.
